UNITED STATES PATENT OFFICE.

ERICH TOENNIESSEN, OF ERLANGEN, GERMANY.

METHOD OF MANUFACTURING A SPECIFICALLY-ACTIVE ALBUMIN SUBSTANCE FROM TUBERCLE BACILLI FOR USE AS A VACCINE.

No Drawing.

Application filed November 24, 1923. Serial No. 676,861.

To all whom it may concern:

Be it known that I, ERICH TOENNIESSEN, a citizen of the German Republic, and a resident of Erlangen, Germany, have invented a new and useful Improved Method of Manufacturing a Specifically-Active Albumin Substance from Tubercle Bacilli for Use as a Vaccine, of which the following is a specification.

10 The vaccines produced hitherto from tubercle bacilli are deficient, although being numerous, in several respects. Fundamentally, two large groups of preparations can be distinguished, viz:

15 Firstly. The old tuberculines (products from the assimilation of foods by the tubercle bacilli). They are not of an albuminiferous nature, nor by themselves able to produce "anti-bodies." In cases of sickness accompanied by fever the old-tuberculine is often times therapeutically not applicable because of its toxic effect. In diagnostics it causes, when applied in a comparatively large dose, often times dangerous heart reactions, while it fails when the dose has been but small. Besides, the dosing of the old-tuberculine cannot be accurate as it cannot be separated from the alimenting bottom and cannot, therefore, be weighed.

20 Secondly. The bacilli bodies. In view of the lacking anti-effect of the old-tuberculine it has been endeavoured to use the bacilli bodies themselves, but these latter, although having been prepared in various manners (so-called opening methods), are possessed of the drawback that they are dissolved in a mammalia organism either not at all or only with difficulty, in consequence whereof the specific albumin substances from the 25 interior of the bacteria cell can render their effect only in an insufficient degree.

In view of this endeavours have been made to extract the albumin substances from the bacilli bodies by various extracting means, such, for instance, as distilled water, diluted alkalies, and acids—mention may be made also of the methods proposed by v. Ruck (Zentralblatt für Bakteriologie; ref. vol. 58, page 244) and by Hoffmann (Wien. Klin. W. 1898)—and to apply them in diluted state to the human body. There were, however, obtained substances which were efficacious either only slightly or not

at all, and that method has, therefore, been abandoned. 55

Thorough experiments have disclosed the fact that it is possible to change the difficultly permeable wax-coverings of the bacilli by means of a special preliminary treatment of the latter, prior to the extracting process, in such a manner, that an albumin substance can now be extracted out of the interior of the bacilli bodies by means of diluted alkali, that albumin substance having never heretofore been obtained, and rendering a very strong effect in the bodies of tuberculous men. 60 65

While the albumin bodies of the tubercle bacilli as obtained by means of the known methods and applied in a dose of from 4 to 10 milligrams cause, with a tuberculous man, only slight skin extractions and only a moderate increase of temperature (as do, for instance, the albumin bodies obtained after v. Ruck's method), the albumin body obtained according to the present improved method causes very intense reactions already when a dose of from $\frac{1}{10}$ milligram has been dispensed. 70 75

It appears from this that this albumin body has not been discovered by the known methods and processes, viz by extracting the bacilli by means of various dissolvents, without a preliminary treatment of the bacilli, and that the present improved method constitutes, therefore, a fundamentally new invention. Over the old-tuberculine the new vaccine presents the advantage of forming a uniform and chemically pure substance which allows of being weighed and, thus, can be accurately dosed. Chemically it differs from the old-tuberculine by the feature that it is an albumin substance (12.6% of nitrogen, positive albumin reactions) and does not contain the specific toxic substance of the old-tuberculine (phosphorus and purinbase containing acid). It is free from phosphorus and purinbases. In spite thereof it renders a very energetic effect even in minute quantities. 80 85 90 95 100

It is hereby proved that the tubercle bacillus contains, besides the old-tuberculine, a substance (briefly termed "tuberculoprotein") having a strong specific effect even in such minute quantities as fractions of a 105

milligram, but being chemically fundamentally different therefrom. According to the present state of physiological chemistry the tuberculoprotein pertains to the group of 5 the "nucleines" as, besides having the properties already stated, it can be precipitated by acetic acid. From the bacilli bodies the tuberculoprotein is distinguished essentially and very advantageously by the feature that 10 it is separated from out of the bacilli bodies and incorporated into a genuine solution. Owing to the tuberculoprotein being in dissolved state, the amount injected (contrarily to the non-resorptive bacilli-bodies) 15 is fully utilized and renders the effect intended.

The new method consists, firstly, in freeing the tubercle bacilli from all products of the assimilation of the food (old-tubercu- 20 line), as well as from the component substances of the alimenting bottom, and then treating it with diluted muriatic acid, whereby the nucleine acid (the most active substance of the old-tuberculine) is separated 25 from the nucleo-proteides and at the same time the extractiveness of the albumin body which is free from nucleine acid is promoted. This albumin body is extracted from the bacilli bodies with the aid of alkali, separated 30 and precipitated by acetic acid, purified by again dissolving it in alkali, precipitating it by acetic acid, and drying it with the acid of alcohol and ether. The tuberculoprotein thus manufactured and obtained in 35 pure state can be preserved in dry condition for any period of time and permits accurate dosing as it can be weighed. .

On the base of the experiments made with the new substance in question for the treatment 40 of men it can be stated that it is of reliable diagnostic and therapeutic effect. The new method is distinguished from one of the known ones especially also by the features that with the latter method the tubercle bacilli are extracted without any preliminary treatment by means of a mixture of 45 strong sodium lye and sodium hypochlorite (the known Uhlenhut's "antiformine") and that the vaccine is then separated from, and precipitated out of, this solution, whereas in 50 the present improved method the bacilli are heated with diluted muriatic acid prior to the extraction, whereby the wax-covering is rendered permeable. Preferably the 55 bacilli are now separated from the acid and extracted only now with the diluted alkali. After that preliminary treatment only a very diluted sodium lye is required for the 60 extraction which contributes greatly to preserving the useful properties of the product.

With the improved method one succeeds 65 already solely by the extraction with diluted alkali in obtaining the still active substance as a uniform one, whereas the known method mentioned in the preceding paragraph re-

quires a successive extraction by strong alkali, acid, and alcohol, so that a mixture of different substances is obtained.

Example: The bacilli of well-grown virulent cultures of the tubercle bacillus are separated from the alimenting liquid by filtering, washed repeatedly with 72% alcohol (by means of a centrifugal machine), and then dried with the aid of 96% and absolute alcohol, and ether, preferably at a 70 temperature not exceeding 40°. The 1 gram of dry tubercle bacillus mass is suspended uniformly by rubbing in 100 gram of 5 per cent muriatic acid. The suspension is heated for 5 minutes on boiling water, then instantly cooled down and rendered moderately alkaline with 30 per cent sodium lye. The liquid obtained is then again repeatedly acidulated with concentrated muriatic acid, and subjected to centrifugal action. The 75 sediment is extracted for 16-24 hours in a 1 per cent potash lye, the mixture stirred repeatedly during that time. The extract is filtered through clay-substances and the clear extract is moderately acidulated with 80 acetic acid, whereafter $\frac{1}{10}$ volume of 10 per cent acetic acid is added. The specific substance precipitates in flaky state, is again washed in water, dissolved another time, with the aid of a centrifugal machine, in a 85 10 per cent potash lye, and again precipitated by acetic acid, washed another time with water, and dried by alcohol and ether, the resulting product being a dry, preservable 90 powder.

I claim:

1. The method of producing a specifically active albumin substance from tubercle bacilli for use as a vaccine, consisting in heating the bacilli in diluted muriatic acid, separating them therefrom, extracting them in an alkali solution, and acidulating the extract with acetic acid so as to separate the 105 albumin body therefrom.

2. The method of producing a specifically active albumin substance from tubercle bacilli for use as a vaccine, consisting in freeing tubercle bacilli from their alimenting liquid, heating them in diluted muriatic acid, separating them therefrom, extracting them in an alkali solution, and acidulating the 110 extract with acetic acid so as to separate the albumin body therefrom.

3. The method of producing a specifically active albumin substance from tubercle bacilli for use as a vaccine, consisting in heating the bacilli in diluted muriatic acid, separating them therefrom, extracting them in an alkali solution, and acidulating the 115 extract with acetic acid so as to separate the albumin body therefrom, and drying this latter by alcohol and ether.

4. The method of producing a specifically active albumin substance from tubercle bacilli for use as a vaccine, consisting in free- 120

ing tubercle bacilli from their alimenting liquid, heating them in diluted muriatic acid, separating them therefrom, extracting them in a diluted alkali solution, acidulating the extract with acetic acid so as to separate the albumin body therefrom, and drying this latter by alcohol and ether.

In testimony whereof I affix my signature in presence of two witnesses.

ERICH TOENNIESSEN.
